COUNTER AND STOP MECHANISM FOR
TEXTILE MACHINERY

William Harry Kimpton, Wilmslow, England, assignor to Celanese Corporation of America, a corporation of Delaware

Application October 3, 1946, Serial No. 700,986
In Great Britain October 8, 1945

4 Claims. (CL. 242—36)

1

This invention relates to textile machinery and specifically to automatic yarn-winding machinery for the winding of pirns, cops, spools and like packages (hereinafter referred to as pirns) in which, when a pirn or group of pirns is completed, an automatic doffing and donning mechanism operates to remove the completed pirns and replace them with empty pirn tubes on which winding proceeds. The invention is particularly concerned with the provision in such machines of a counter and stop mechanism adapted to stop the machine after a predetermined number of pirns has been wound.

U. S. Patent No. 2,173,160 of September 19, 1939, describes an automatic pirn-winding machine provided with a mechanism of this character, the counter being operated step by step on the completion of each group of simultaneously wound pirns by a part of the mechanism employed in the doffing and donning operation. The doffing and donning operation is initiated by freeing a spring-loaded clutch member and the counter and stop mechanism acts, after a predetermined number of pirns has been wound, by releasing the spring loading of said member and thus preventing further doffing, donning or winding. In this way the machine can readily be arranged to stop, without attention, before the exhaustion of the supply of yarn available to the machine or of the supply of empty pirn tubes. It is an object of the present invention to provide a counter and stop mechanism that is simpler in construction, more certain in operation and in other respects superior to that previously employed.

According to the present invention an automatic yarn-winding machine comprises a counter and stop mechanism adapted to be operated step by step by a member of the machine that moves to initiate a doffing and donning operation of the machine, said mechanism being adapted, after a predetermined number of such steps, to act on said member so as to prevent further movement thereof. It is preferable that the member operating the mechanism should not be positively actuated, but should be operated, for example, through a spring or by gravity, the counter and stop mechanism being adapted merely to bring a stop into the path of its movement whereby such movement is prevented, without the necessity of disconnecting the member from the part of the machine which operates it. The counter and stop mechanism in this form, i. e. comprising a stop member adapted to block the movement of the member operating the

2

counter, may be regarded as a separate attachment applicable in any appropriate manner to an existing automatic yarn-winding machine.

The counter and stop mechanism according to the invention may be applied to the machine described in U. S. Patent No. 2,173,160, of September 19, 1939, referred to above, and to other automatic pirn-winding machines in which doffing and donning can be prevented by preventing the movement of a member which initiates the doffing and donning operation. For example the mechanism may be applied in the automatic pirn-winding machine described in U. S. Patent No. 2,306,268 of December 22, 1942, or in that described in U. S. application S. No. 700,985, filed October 3, 1946. Where a machine does not comprise a negatively actuated member in the mechanism for initiating the doffing and donning operation, it may be desirable to adapt the machine for this purpose, for example by the insertion of a spring connection in place of a solid connection in the chain of mechanism by which doffing and donning is started.

By way of example one form of counter and stop attachment applicable specifically to the automatic pirn-winding machines described in U. S. Patent No. 2,306,268 of December 22, 1942, and in U. S. application S. No. 700,985, filed October 3, 1946, will now be described in greater detail with reference to the accompanying drawing in which:

Fig. 1 is an end view showing the clutch means for driving the doffing and donning mechanism.

Fig. 2 is an elevation of the counting mechanism.

The machine is one in which doffing and donning is brought about by the rotation, through a single revolution, of a cam shaft 1 carrying a series of cams (not shown) adapted to bring about the various operations necessary for doffing and donning. The cam shaft 1 is driven through a single revolution from a constantly rotating clutch member 2. The clutch member 2 is in the form of a disc, freely mounted on the cam shaft 1 and arranged face to face with a large disc 3 secured to the cam shaft. The disc 2 has four semicircular notches round its periphery, while the disc 3 carries a pair of spring-loaded levers 5, 6 mounted on axes parallel to the cam shaft 1. The lever 5 lies approximately tangential to the disc 2, pointing in the direction of rotation thereof, and is lightly spring-loaded outwards by means of a spring coiled about its pivot spindle, its shaped free end 7 being held clear of the edge of the disc 2 and the notches 4 as the

disc rotates. The second lever 6 is approximately radial to the cam shaft 1 and its free end 8 is bent through a right angle so as to engage the outer surface 9 of the lever 5, the said outer surface 9 being sloped in the form of a ramp so that movement of the lever 6, under the action of its spring 10, drives the lever 5 inwards. The lever 6 is held against the action of its spring 10 and out of engagement of the lever 5 by means of a catch lever 11 mounted on a spindle 12 parallel to the cam shaft 1. The spindle 12 tends to rotate counter-clockwise, by gravity or by spring-loading, but is prevented from doing so by the engagement of a lever 13 on the spindle 12 with the end of a lever 14 attached to the starting and stopping handle 15 of the machine. The bulk of the mechanism, above and below the baseplate 16 is omitted for the sake of clarity, but is described in detail in U. S. application S. No. 700,985, filed October 3, 1946.

On the completion of a pirn, the normal stopping mechanism of the pirn winding machine comes into action, as a result of which the handle 15 is moved upwards to the stop position and this, through the lever 14 allows the spindle 12 to rotate and the catch lever 11 to rise, and so releases the lever 6. The lever 6 acts on the back of the lever 5 so as to drive it inwards and to hold its shaped end 7 in engagement with the next notch 4 encountered in the edge of the driving disc 2. In this way the disc 2 draws the disc 3 carrying the two levers 5, 6 round with it, and rotates the cam shaft 1 through one revolution. At the end of one revolution the lever 6 encounters the catch lever 11, which by this time has returned to its original position, and releases the lever 5 so as to stop the driving of the cam shaft 1.

The counter and stop attachment of the present invention is arranged to be operated from lever 18 fixed to the spindle 12 carrying the catch lever 11. The attachment comprises a circular casing 19 secured to the frame of the machine 20 and containing, on a central spindle 21, a numbered disc 22 (largely broken away in Fig. 2) fitting inside the casing 19. To the disc 22 is secured a ratchet wheel 23 having a number of teeth at least as great as the greatest number of pirns desired to be wound, the numbers on the edge of the disc corresponding in angular position to the teeth of the ratchet wheel 23. The numbers are arranged to show through an aperture 24 in the face of the casing 19, so displaying the number of pirns already wound. The central spindle carries a radial lever 25 on which is mounted a pawl 26 adapted to engage the ratchet wheel 23. A second or stop pawl 27 is pivoted to the body of the casing 19. The movement of the lever 25 is limited by a stop 28 fixed to, and projecting forward from, the back of the casing 19 adapted to engage with the tail 29 of the pawl 26 and raise the pawl out of engagement with the ratchet wheel 23 for a purpose described hereafter.

The lever 18 extends through a slot in the side of the casing 19 and engages with the lever 25 on the central spindle 21. When the lever 18 moves, it allows the lever 25 to fall, the pawl 26 riding over one tooth of the ratchet wheel 23 which is held by the stop pawl 27. On completion of the doffing and donning operation the lever 18 is raised, thus raising the lever 25 and the pawl 26 and rotating the ratchet wheel 23 against the action of a spring 32 through a distance of one tooth. The spring 32 is secured at

its inner end to a boss 33 of the ratchet wheel 23 on which the disc 22 is mounted, and at its outer end to the stop pin 28. Round the edge of the numbered disc 22 and close to each of the numbers is a perforation 30, into one of which, corresponding to the number of pirns to be wound (the number 10 in the device as shown) is inserted a stud 31. In due time rotation of the disc 22 drives the stud 31 into engagement with the lever 18 and prevents it from moving. On the next movement of the starting and stopping lever 15 of the machine the spindle 12 does not rotate, being held by the pin 31 and lever 18. In this way the doffing and donning mechanism is prevented from operating, and the machine remains idle until it receives attention.

In order to reset the counting attachment a button 35 projects from the bottom of the casing, the upper end of which engages with and releases the tail 36 of the stop pawl 27. This releases the ratchet wheel 23 and allows the wheel 23 and disc 22 to rotate backwards under the action of the spring against which they are rotated in the course of counting. During the first part of the backward rotation, the lever 25 and pawl 26 also rotate, the lever 18 being also free to move since it is no longer restricted by the stud 31 in the disc 22. In due course the tail 29 of the pawl 26 engages the stop 28 and is released from the ratchet wheel 23, which then, unimpeded by either pawl, rotates to a zero position determined by a back-stop (not shown) acting on the disc 22.

The central spindle 21 of the counting adjustment may be connected through a free wheel device to a counter of ordinary form which is thus adapted to indicate the total number of pirns wound on the machine.

Having described my invention, what I desire to secure by Letters Patent is:

- 40 1. In an automatic pirn-winding machine comprising doffing and donning mechanism and a member adapted to be moved to initiate a cycle of action of said doffing and donning mechanism, an attachment comprising a counting device adapted to operate step by step by the motions of a part separate from the counting device and attached to said member, a spring, a stop adapted to be brought, after a predetermined number of said steps, against the action of said spring into the path of said part so as to prevent further motions of said part and said member, and release mechanism for said stop permitting resetting thereof to a zero position under the action of said spring.
- 45 2. In an automatic pirn-winding machine comprising doffing and donning mechanism and a member adapted to be moved to initiate a cycle of action of said doffing and donning mechanism, an attachment comprising a counting device including a ratchet wheel, a lever adapted to be engaged and rocked by the motions of a part separate from said counting device and attached to said member, a pawl on said lever adapted to actuate said ratchet wheel step by step, and a stop fixed to said ratchet wheel and adapted to be brought, after a predetermined number of such steps, into the path of said part so as to prevent further motions of said part and said member.
- 50 3. In an automatic pirn-winding machine comprising doffing and donning mechanism and a member adapted to be moved to initiate a cycle of action of said doffing and donning mechanism, an attachment comprising a ratchet wheel, a numbered disc carried by said ratchet wheel and
- 55
- 60
- 65

- 75

having a recess corresponding to each number thereon, a lever adapted to be engaged and rocked by a part attached to said member, a pawl on said lever adapted to actuate said ratchet wheel step by step, and a stop pin adapted to be received and carried in any of said recesses and to be brought, after a predetermined number of such steps, into the path of said part so as to prevent further motions of said part and said member.

4. In an automatic pirn-winding machine comprising doffing and donning mechanism and a member adapted to be moved to initiate a cycle of action of said doffing and donning mechanism; an attachment comprising a spring, a ratchet wheel, a numbered disc carried by said ratchet wheel and having a recess corresponding to each number thereon, a lever adapted to be engaged and rocked by a part attached to said member, a pawl on said lever adapted to actuate said ratchet wheel step by step against the action of said spring, a stop pin adapted to be received and carried in any of said recesses and to be

10

brought, after a predetermined number of such steps, into the path of said part so as to prevent further motions of said part and said member, and release mechanism for said stop pin permitting re-setting of the ratchet wheel to a zero position under the action of said spring.
